UNITED STATES PATENT OFFICE.

MERRITT GALLY, OF NEW YORK, N. Y.

MECHANICAL MUSICAL INSTRUMENT.

SPECIFICATION forming part of Letters Patent No. 351,172, dated October 19, 1886.

Original application filed April 23, 1885, Serial No. 163,190. Divided and this application filed October 24, 1885. Serial No. 180,845.
(No model.)

To all whom it may concern:

Be it known that I, MERRITT GALLY, residing at New York city, in the county of New York, and State of New York, have invented 5 certain new and useful Improvements in Mechanical Music-Sheet Motors, of which the following is a specification, reference being had therein to the accompanying drawings.

This invention relates to sheet motors for 10 mechanical musical instruments.

The object of the invention is to connect the music-sheet winder or other propelling device to a wind-motor, and the motor with the bellows of the instrument, or with an additional 15 bellows connected with the pedal or pedals of the instrument; also, to connect with the wind-motor a valve and an index for controlling and indicating the time of the music.

In the drawings, Figure 1 is a plan view of 20 a music-sheet and its motor. Fig. 2 is a partial elevation and partial section of motor and bellows attachment. Fig. 3 is an end elevation of friction - retarder. Fig. 4 is a plan view of the cylindrical casing of motor. Fig. 25 5 is a side view, partly sectional, of motor-wheel, with valve and adjusting-pointer. Fig. 6 is a plan view, partly sectional, of the valve with the adjusting pointer and index. Fig. 7 is a diagram of windway and automatic valve.

30 D indicates a fan-wheel, which is inclosed in cylindrical casing C, and is operated, preferably, by the exhaust of air, but may be operated by compressed air.

The pedal A and bellows B may be of any 35 usual construction.

The gear K on the shaft of the fan-wheel meshes with gear l on shaft u, and through a gear on this shaft the take-up roll E is driven, and by the movement of the take-up roll the 40 music is drawn from roll F.

A pointer, a, on shaft c can be swung with 45 the shaft, and thus indicate on sector-index b the position of valve a', which turns with shaft c and opens passage i more or less, thus determining the amount of air which may pass 50 through the motor. By swinging the pointer a and valve a' the opening i may be made to pass such an amount of air as will regulate the movement of the wind - motor to the desired 55 speed.

It is apparent from Figs. 2 and 5 that the

valve a' may be at either side of passage d, provided the automatic valve j is not used.

In order that the graduated arc b may be graded to represent "metronome," or other 55 desired time, I construct the valve a' with an opening, J, therethrough, as shown in Fig. 6, and make the opening i of the valve-seat varying in width at different points, as shown by the dotted lines. The shape of the opening i 60 may be varied according to the kind of time or movement to be produced, and the arc b may be figured to correspond, and also corresponding figures placed upon the music-sheet.

The port J of valve a', when moved to the 65 narrow end of the opening i, will pass only a sufficient quantity of air to drive the motor at its lowest speed, the amount being gradually increased as the pointer is moved to the right on arc b.

A simple cut-off valve without the opening J may be used in connection with port i of the valve-seat; but the valve as shown is preferable, as the movement may be stopped with the pointer at either end of the graduated arc, 75 and the construction of the valve and ports be more easily made to produce the proper gradations in time.

The bellows B, Fig. 2, may be that which 80 operates the musical instrument, or it may be an additional bellows used only for operating the motor. The bellows-reservoir may be operated in connection with either spring or weight, as the case may require. If the tension of the air of the bellows is variable, I use 85 an automatic valve, j, Fig. 5, to more or less open and close the windway i in proportion to the variation of the air tension. The valve j is connected by link L² to the movable bellows-board of a pneumatic motor, N². This 90 pneumatic motor is in constant connection with the air of the bellows and closes against its spring P² in proportion to the tension of the air.

The movement thus produced acts on the valve j and closes more or less in accordance with the air-tension the windway i. This preserves an invariable movement of the wind-wheel when the valve a' is set at any given point. Fig. 7 is a diagram showing a plan of the windway i and automatic valve j, 95 the dotted lines showing the position of the valve when partly closing the windway.

The usual shape of the orifice R of an ordinary wind-wheel is circular, but I find that in combination with a musical instrument it is better in the elongated form shown in Fig. 5 4. With this form of opening, as R, much less noise is produced by the passage of the air, and a less amount of air is required, as it is directed to a line across the extreme end of the fans where it has the greatest amount of 10 leverage. The difference in the amount of noise produced by the rushing wind between this shape of orifice and a circular one is very great, making the construction shown very desirable.

15 The air from the motor may pass through chamber a¹ to the aperture i, or by a more direct connection, as desired.

As the movement of the sheet is somewhat accelerated by the increase of the roll E in 20 winding, I apply a retarding device as follows: Pulley O is on an extension of roll E, and a narrow tape, M, winds on the pulley as the music-sheet winds on roll E. A spring friction-piece, F, bears against the face of the 25 tape, and as the size of the roll of tape M increases so does the pressure of the friction-piece on the tape increase. The tape M and its winding devices may bear any proportional relation to the music-sheet and its winding 30 devices, and may be permanently or detachably connected therewith.

In my application No. 163,190, filed April 23, 1885, I show and claim certain modifications of the valve-controlling mechanism and 35 of the friction sheet-retarding device. The present application is a division of said application No. 163,190, with additional features.

I do not herein claim the combination, with a take up roller for the music-sheet, of a wind- 40 wheel motor inclosed in a drum, the same being claimed in my application No. 163,190, filed April 23, 1885.

In my said application filed April 23, 1885, No. 163,190, I make broader claims on the

pneumatic governing device for a wind-motor 45 and to the wind-wheel incased in a drum and operated by the exhaust, and to a spring friction-brake. Therefore I do not broadly claim these devices in this application.

I claim—

1. The combination, with the take-up roller for the music-sheet, of a wind-motor, a valve for controlling the same, the valve-seat having its opening varying in width at different 50 points to facilitate graduation of the move- 55 ment of the motor.

2. The combination, with the take-up roller for the music-sheet, of a wind-motor, a valve for controlling the same, the valve-seat having its opening varying in width at different 60 points, and the valve having an opening therethrough, substantially as specified.

3. The combination, with the wind-motor for the music sheet of a mechanical musical instrument and its bellows, of a valve opera- 65 ted automatically by means of the air of the bellows to vary the supply of air for the motor in accordance with the variation of air-tension of the bellows.

4. The combination, with the wind-motor, 70 of the windway and its valve and the automatic pneumatic motor N², substantially as and for the purpose specified.

5. The combination, with the sheet-winding roll, of a supplementary tape and a friction 75 device bearing on the surface of said tape.

6. In combination with the sheet-winding mechanism of a mechanical musical instrument, a wind-wheel motor and a cylindrical casing inclosing the same, said casing having 80 a port in its periphery elongated in the direction of the length of the cylinder, as set forth.

In testimony whereof I affix my signature in presence of two witnesses.

MERRITT GALLY.
